ERNEST CECIL COPE, OF SPONDON, NEAR DERBY, ENGLAND, ASSIGNOR TO CELANESE CORPORATION OF AMERICA, A CORPORATION OF DELAWARE

ELECTRICAL DRIVING OF SPINDLES FOR SPINNING, TWISTING, DOUBLING, WINDING, AND ANALOGOUS PROCESSES

Application filed July 3, 1928, Serial No. 290,034, and in Great Britain July 16, 1927.

This invention relates to textile spindles and electrical means for driving the same, for use in spinning, twisting, doubling, winding and analogous operations on natural or artificial fibres, filaments, threads or 5 yarns, more specially at high or very high speeds, examples of such textile operations being high speed spinning, twisting or doubling of threads or yarns of artificial or 10 natural fibres or filaments by cap, ring and traveller, flyer or other methods winding or twisting and winding artificial filaments continuously with their production either by the wet coagulation method or by the dry 15 or evaporative method, and especially cap spinning (i. e. cap twisting and winding) of artificial filaments continuously with their formation by the dry or evaporative method; crêpe twisting or doubling of 20 threads or yarns of artificial or natural filaments or fibres wherein a high twist is required to be imparted to the threads or 25 yarns or in the doubling of the same.

An object of the invention is to enable 30 one or any desired number of textile spindles to be driven at high or very high speeds by electrical driving means comprising a polyphase high frequency generator and one or more polyphase motors, the generator or the motor or motors, or the generator and the motor or motors having unbalanced windings. By the phrase "unbalanced windings", it is to be understood that 35 each phase of the unit so provided has a number of ampere turns differing from those on each of the other phases thereon.

It was found that a higher or very high speed could not be satisfactorily obtained or maintained when employing the known 40 polyphase electric motors fed by the known types of polyphase generator, which motors and generators have balanced windings i. e., windings having an equal number of "ampere turns" on each phase.

45 It was found that on attempting to work such motors at the requisite high or very high speeds when fed by such generators, that during acceleration the motors, and consequently the textile spindles to which 50 their rotors are directly connected, are very

liable to remain at the first, second or other critical speed and that the motors can only be accelerated past such critical speeds by careful manipulation of the generator voltage and frequency, and even if it is managed to accelerate past a critical speed the speed is very unstable and the motors have every tendency to slow down to a critical speed. It may be explained that a critical speed is a period during acceleration of the 55 rotor when the negative torque due to harmonics of the supply rises in value to a degree sufficient to balance positive main torque, the result being that acceleration is arrested and the rotor speed becomes stable 60 at some submultiple of the synchronous speed. These harmonics accompany all wave forms of electrical energy generated by rotating machines, but their influence appears to be much more manifest at the high frequencies which are necessary to employ for 65 obtaining the high or very high speeds. Thus on applying a polyphase current of the necessary high frequency to the motor 70 with the object of obtaining high or very high speeds, a point is reached beyond 75 which the rotor refuses to accelerate, owing to the combination of the eddy currents formed in the rotor and which are evenly disposed about the rotor. In practice it was 80 found for example that with the high frequency current necessary to obtain the high or very high speeds the first and second critical speeds which developed during acceleration were at about 5,000-6,000 and 85 11,000-12,000 revolutions per minute, respectively.

By means of the present invention textile spindles may readily be driven at high or extremely high speeds. It is believed that the reason why the obtainment of such speeds is rendered possible is that on the 90 rotor arriving at any critical speed at which an extra torque is required to overcome the electrically unbalanced forces, an increase in current results, followed by a corresponding increase in the magnetic flux passing through the rotor core, and that, owing to the unbalanced windings, a strong magnetic couple is formed in the rotating field which is 95 100

moving much faster than the field (the slip at this point being of course, considerable) the tendency of which magnetic couple is to jerk or whip the rotor over the critical speed. Once past this point, the speed of the rotor rapidly increases, accompanied by falling current, until perhaps another critical speed is met, with a repetition of this particular action, and finally the rotor reaches a synchronous speed governed by the periodicity of the supply and percentage of slip.

By means of the present invention the motors can rapidly attain the desired high or very high speeds, it having been found in practice possible to attain for example a synchronous speed of 20,000 revolutions per minute in as short a time as about 14 seconds.

According to my invention, therefore, apparatus for use in textile operations comprises in combination one or more textile spindles, one or more polyphase (preferably not less than three phase) motors, a polyphase high frequency generator for driving the motor or motors, the motor or motors and/or the generator having "unbalanced windings", and driving means arranged between the motor or motors and the spindle or spindles.

In performing the invention one or any number of textile spindles may be driven, by one motor (or it may be one of the motors) fed by the high frequency generator; and further, the textile spindle or spindles may be driven at the same speed as the motor driving the same or at a higher or lower speed.

An advantage of the invention is that several or any desired number of spindles may be driven from one motor of the electrical driving means, instead of a separate motor having to be employed for each spindle to be driven, though of course a single spindle can be separately driven by a corresponding motor if desired. Where the electrical driving means comprises a number of motors supplied by the high frequency generator, each of them may drive any desired number of spindles.

The motor (or motors) or the high frequency generator supplying the same, or it may be both the motor (or motors) and the high frequency generator supplying them may be provided with the "unbalanced winding." For the best functioning of the apparatus the difference in the number of ampere turns between the two phases exhibiting maximum difference should not exceed about 15% and preferably should not exceed from about 10% to about 12%, but it is of course understood that I do not limit myself in this respect.

In the preferred form of the invention I

obtain the differing number of "ampere turns" by winding the phases with a differing number of turns of wire. I may however obtain the differing number of "ampere turns" by employing both on the motor or motors and the generator an equal number of turns of wire as between phase and phase, and by inserting between the generator and motor or motors a transformer (either static or rotary) wound with a differing number of turns of wire on each of the phases, or by including in the circuits of each of the phases (or it may be on each of the phases except one) resistances or chokes—which in cases where they are included in the circuits of two or more phases are of different value as between phase and phase—, or by employing any other known means for causing polyphase current to be supplied at a different voltage on each phase.

It will be seen that in each form of the invention the number of ampere turns on the motor or motors and/or the generator will be different on each phase, as either the number of turns of wire or the current will be different on each of the phases.

The rotors of the motors may be of the ordinary squirrel cage type or may be provided with closed windings, the former, however, being preferable.

I may also, though with less advantage, employ rotors wound with open windings and provided with slip rings, in which case both stator and rotor are preferably provided with open windings (of which either or both may be "unbalanced windings"), though the stator may be of the squirrel cage type or wound with closed coils.

The accompanying drawings illustrate by way of example several ways of carrying out the present invention, it being of course understood that they are given by way of illustration and are in no way limitative.

Fig. 1 is a development diagram showing the method of winding the stator of a motor which may be employed in the apparatus shown in Figs. 6-9;

Fig. 2 is a vertical section through the motor;

Fig. 3 is an elevation of part of the rotor;

Figs. 4 and 5 are horizontal sections of the stator and rotor respectively on the line 4-4 of Fig. 2;

Fig. 6 is a side elevation of a spinning frame showing a single spindle driven from a corresponding motor through the intermediary of belt and pulley gearing. This arrangement may be employed for driving a hollow spindle through which a rod carrying a cap may pass, as used in cap-spinning apparatus;

Fig. 7 shows a number of spindles driven by a single motor;

Fig. 8 shows an alternative method of

driving a number of spindles by a single motor; and

Figs. 9 and 10 show two views to an enlarged scale of a detail of Fig. 8, Fig. 9 being an elevation, a part being an irregular section on the line 9—9 of Fig. 10, and Fig. 10 being a plan, a part being a section on the line 10—10 of Fig. 9.

Referring to Fig. 1, A, B and C represent the commencement of the windings of the first, second and third phases respectively, while the line D E F represents the common point or junction of the windings.

The first phase winding starts at A and makes a number of turns between the stator slots 1 and 12, then a number of turns between slots 2 and 11, then a number of turns between slots 24 and 13 and finally between slots 23 and 14, the end of the first phase winding joining the common junction of the phases at the point E.

The total number of turns on the first phase windings in the examples described and illustrated is 100.

25 The second phase winding starts at B and makes a number of turns between the stator slots 9 and 20, then a number of turns between slots 10 and 19, then a number of turns between slots 8 and 21 and finally between slots 7 and 22, the end of the second phase winding joining the common junction of the phases at the point F.

The total number of turns on the second phase winding in the examples described and illustrated is 97.

35 The third phase winding starts at C and makes a number of turns between the stator slots 17 and 4, then a number of turns between slots 18 and 3, then a number of turns between slots 16 and 5 and finally between slots 15 and 6, the end of the third phase winding joining the common junction of the phases at the point D.

The total number of turns on the third phase in the examples described and illustrated is 94.

Referring to Figs. 2, 3, 4 and 5. The motor shaft 1 runs in bearings 2, 3 and rigidly fixed to it is a squirrel cage rotor 4. The bearings 2, 3 preferably present a series of grooves or spiral grooves 5 and lubrication may be effected by supplying lubricant to one end of the grooves by pipes 6 and withdrawing it at the other end by pipes 7, a continuous circulation being maintained by a pump or pumps (not shown), or by gravity feed. The stator core 8 is rigidly fixed to the enclosing casting 9.

60 The rotor 4 is similar to the usual type of squirrel cage rotor, comprising a laminated iron core built up from soft iron stampings 10 (care being taken to ensure good insulation between the stampings) and 65 having copper squirrel cage bars 11, pass-

ing through the rotor slots and fixed into the squirrel cage end rings 12, the rotor slots being split, as shown in Fig. 5. The bars 11 are staggered to give ease in starting, and also to provide ventilation in the following manner:—The bars 11, being staggered, cause the split slots of the rotor to be likewise staggered, and thus the staggered grooves or channels 13 formed on the outer face of the rotor draw air in through holes 14 in one end 15 of the motor casting 9, through the armature tunnel, and out of holes 16 in the other end 17 of the motor casing.

The stator core 8 is built up from laminated slotted soft iron stampings 18 (good insulation again being provided between the stampings), and the slots 19 are provided with highly insulating lining 20 and with the unbalanced winding 21, of which Fig. 1 is the development diagram. The stator slots are not staggered in the motor shown, but in the case where the rotor bars 11 are not staggered, the stator slots are preferably staggered to give ease in starting. A flywheel may be rigidly fixed to the shaft 1, or when a coupling member 22 is used, it may conveniently be made large enough to serve as a flywheel.

25 Referring now to Fig. 6, a motor 23 carried by the machine frame 24 is provided with a pulley 25 driving a belt 26. The belt passes round a pulley 27 running in bearings 28 carried by a rail 29, and round a jockey or tension pulley 30 mounted in a skew forked arm 31 of a lever 32 pivoted on a bar 33 and counter-balanced by a weight 34. On leaving the pulley 30, the belt passes round a wharf 35 formed on a bobbin carrier 36 carried by a rail 37. On a spindle 38 passing through the bobbin carrier 36 is a cap 39, movable relatively to the bobbin 40, as will be well understood, either by the traversing of the rail 37 or of the spindle 38 by any of the means well known in the art. Instead of a motor driving each separate spindle, a shaft running over the length of several spindles and carrying an extended pulley or a series of pulleys may be driven from a motor directly coupled or in geared connection with the shaft, the spindles being driven in the manner described above from the pulley or pulleys.

In Fig. 7, a motor 41 drives a vertical shaft 42 through a worm 43 and a worm-wheel 44, the shaft 42 running in bearings 45 in an end frame 46 of the machine. Between the bearings 45, the shaft 42 carries a pulley 47 which drives a belt or band 48 passing along the length of the machine to a second pulley 49 mounted between the bearings 50 of a shaft 51 carried by a second end frame 52, the belt returning to the pulley 47 along the back of the machine. 130

The end frames 46, 52 are connected by rails 53, the upper one of which supports spindle carriers 54, and the belt 48 is arranged to pass alternately under and over wharls 55 carried by spindles 56 rotatably mounted in the carriers 54. Preferably two lines of spindles are driven by the belt 48, the second line being mounted on a rail running along the back of the machine.

10 In either of the forms of apparatus shown in Figs. 6 and 7, any suitable ratio may be chosen for the gearing between the motor and the spindle or spindles, but usually the ratio will be such that the speed of 15 the spindles will be equal to or greater than that of the motor, though a slower speed may be obtained if desired.

In the form of apparatus shown in Fig. 8, a motor 57 is directly coupled to a shaft 20 58 running in bearings 59 in the machine frame or carried by it. Spindles 60 are mounted in bearings 61, 62 in rails 63, 64 of the machine frame and are driven from the shaft 58 by pairs of helical gears 65, 66. 25 Preferably the gears 65, 66 have a 1:1 ratio, enabling the spindles 60 to be driven at the same high speed as the motor 57, but other gear ratios may be chosen, as desired. In order to minimize the thrust on the shaft 30 58, alternate gears 65 preferably have their teeth cut in reverse directions, the corresponding alternate spindles 60 thereby receiving rotation in opposite senses. By these means, twist can be imparted in opposite directions to the threads being unwound from alternate bobbins carried by the rapidly rotating spindles.

In view of the extremely high speeds of the gears 65, 66, these gears are preferably 40 enclosed in casings generally designated at 67 and shown in greater detail in Figs. 9 and 10. The lower half 68 of the gear casing is carried by the rail 64, and the upper half 69 is secured to the lower half by 45 bolts and nuts 70, 71. Felt washers 72 may be provided to prevent the escape of lubricant from the casing. Any suitable means may be provided to introduce lubricant into the casing and to drain the casing, and 50 preferably means are provided to maintain a continuous flow of lubricant through the casing, either by forced or gravity feed.

What I claim and desire to secure by Letters Patent is:—

55 1. Apparatus for driving textile spindles at ultra high speeds, said apparatus comprising in combination a driving unit consisting of a polyphase high frequency generator, a driven unit consisting of at least one polyphase motor driven by said generator, at least one of said units having unbalanced windings, a plurality of textile spindles, and driving means adapted to be operative between the driven unit and the 60 65 textile spindles.

2. Apparatus for driving textile spindles at ultra high speeds, said apparatus comprising in combination a driving unit consisting of a polyphase high frequency generator, a driven unit consisting of at least one polyphase motor driven by said generator, at least one of said units having unbalanced windings, a plurality of textile spindles, and toothed gearing adapted to be operative between the driven unit and the 70 75 textile spindles.

3. Apparatus for driving textile spindles at ultra high speeds, said apparatus comprising in combination a driving unit consisting of a polyphase high frequency generator, a driven unit consisting of a polyphase motor driven by said generator, at least one of said units having unbalanced windings, a plurality of textile spindles, and a shaft driven by the motor, toothed gears 80 on the shaft, and a toothed gear on each spindle intermeshing with said gears on the shaft.

4. Apparatus for driving textile spindles at ultra high speeds, said apparatus comprising in combination a driving unit consisting of a polyphase high frequency generator, a driven unit consisting of a polyphase motor driven by said generator, at least one of said units having unbalanced 90 windings, a plurality of textile spindles, and a shaft driven by the motor, helical gears on the shaft, and a helical gear on each spindle intermeshing with said gears on the shaft.

5. Apparatus for driving textile spindles 100 at ultra high speeds, said apparatus comprising in combination a driving unit consisting of a polyphase high frequency generator, a driven unit consisting of a polyphase motor driven by said generator, at 105 least one of said units having unbalanced windings, a plurality of pairs of oppositely rotatable textile spindles, and a shaft driven by the motor, toothed gears on the shaft, and a toothed gear on each spindle intermeshing with said gears on the shaft.

6. Apparatus for driving textile spindles at ultra high speeds, said apparatus comprising in combination a driving unit consisting of a polyphase high frequency generator, a driven unit consisting of a polyphase motor driven by said generator, at least one of said units having unbalanced windings, a plurality of pairs of oppositely rotatable textile spindles, and a shaft driven 115 by the motor, helical gears on the shaft, and a helical gear on each spindle intermeshing with said gears on the shaft.

In testimony whereof, I have hereunto subscribed my name.

ERNEST CECIL COPE.
